UNITED STATES PATENT OFFICE.

THOMAS SHEPHERD, OF DINGMANS FERRY, PENNSYLVANIA.

HORSESHOE AND CALK.

1,157,052.

Specification of Letters Patent. Patented Oct. 19, 1915.

Application filed March 15, 1915. Serial No. 14,432.

To all whom it may concern:

Be it known that I, THOMAS SHEPHERD, a citizen of the United States, residing at Dingmans Ferry, in the county of Pike, State of Pennsylvania, have invented certain new and useful Improvements in Horseshoes and Calks; and I do hereby declare the following to be a full, clear, and exact description of the invention, such as will enable others skilled in the art to which it appertains to make and use the same.

This invention relates to certain novel and useful improvements in horse shoes, and has particular application to the construction of a removable calk for the shoe.

In carrying out my invention it is my purpose to provide a detachable calk, the body portion of which is composed of relatively soft metal, said body portion having a tapered central longitudinal bore therethrough which is adapted to receive a core of relatively hard metal, such as steel, which is tapered to conform to the taper of the bore. The result is that the metal of the body portion being softer than the metal of the core will wear more quickly when in use, and therefore, as the material of the body around the point of the core wears down, the end of the relatively hard core will be left projecting beyond the outer end of the calk, and thus always provide a firm, sharp gripping point for engagement with slippery surfaces or wet ground. Inasmuch as the core and the bore into which it fits are tapered, the core will be held against working out of the bore and thus being lost, and at the same time the wedging action of the core against the body portion of the calk will have a tendency to bind the latter more firmly in the shoe.

It is also my purpose to provide a calk for horse shoes which will embody the desired features of simplicity, efficiency, safety and reliability when in use, and which may be manufactured and marketed at a relatively low cost.

With the above recited objects and others of a similar nature in view, my invention consists in the construction, combination and arrangement of parts set forth in and

falling within the scope of the appended claims.

In the accompanying drawings: Figure 1 is a perspective view of a horse shoe equipped with calks embodying my invention. Fig. 2 is a cross sectional view taken through one of the calks and the shoe on the line 2—2 of Fig. 1, the calk being shown in elevation. Fig. 3 is a cross sectional view taken on the line 3—3 of Fig. 2. Fig. 4 is a perspective view of the wedge.

Referring now to the accompanying drawings in detail, the letter A indicates a horse shoe as an entirety with the heel portions flattened at the tread faces as at *a* and provided with the threaded recesses for the reception of the calks C. The tread face of the shoe, at opposite sides of the center of the toe is thickened and widened and beveled to form bosses 2 on the tread face of the shoe at the toe, these bosses slanting downward from the outer toward the inner edge of the shoe. Each of these bosses is also provided with a threaded bore 1 which is inclined upwardly and rearwardly, each bore being adapted to receive one of the calks C, which will be hereinafter described in detail. I will explain that while the recesses at the heel portions of the shoe are made straight or vertical so that when the horse's hoof rests flat upon the ground, the calks threaded into the heel recesses will project perpendicularly to the ground, the front calks are inclined or projected forwardly when the hoof rests upon the ground. Now, as the tendency of the animal is to dig the toe into the ground in first taking hold of the surface of the ground in stepping, by inclining the calks at the toe as mentioned, I insure that such calks will always be in position to obtain a firm grip upon the ground, thereby obviating the possibility of slipping which is usually the case where the toe calks are arranged at right angles to the tread surface of the shoe.

In the drawings I have shown my preferred form of calk wherein the calk C comprises a tubular cylindrical shank section 3, having its exterior wall threaded as at 4 so that the shank may be threaded into one of

the threaded recesses of the shoe. The body of the calk is indicated by the numeral 5 and is formed integral with the shank and is preferably rectangular in cross section with 5 the sides tapered or beveled. The body of the calk is preferably made of relatively soft metal, such as iron or soft steel and is provided with a central longitudinal bore 7 which is also preferably square in cross 10 section, this bore being also tapered, and with its widest end 8 communicating with the hollow shank 3, while its narrow end opens through the ground engaging ends 9 of the body of the calk. The numeral 10 indicates a pin or core which is also square in cross section to conform to the shape of the bore or the body of the calk, this pin being likewise tapered to correspond to the taper of the bore, the major portion of its length. 15 20 The core or pin 10 is formed of relatively hard metal, such as steel, and is preferably made slightly longer than the total length of the calk itself, including the shank of the latter. The portion 11 of the core which extends into the hollow shank 3 is tapered in the opposite direction to its major portion which lies within the bore of the calk body. The inner end 12 of the core is adapted to bear against the bottom of the recess 1, while 25 30 the outer tread or ground engaging end 13 of the core projects slightly beyond the tread face 9 of the calk body. Thus it will be seen that by tapering the pin or core it cannot work outward through the calk body and be lost, but will be firmly wedged therein, and at the same time will have a tendency to spread the relatively softer metal of the calk body and so assist in binding the shank in the recess. Likewise the inner end 12 of 35 40 the core bearing against the bottom wall of the recess will limit the inward movement of the core, and at the same time the core, on projecting entirely through the shoe will not strike against the horse's hoof and thereby injure the same.

From the above description, taken in connection with the accompanying drawings, the construction and manner of employing my invention will be readily apparent. 50 When it is desired to insert a calk in the shoe, the tubular threaded shank is screwed into the threaded recess and the inner end 12 of the core will bear against the bottom recess. Thus the inward movement of the 55 calk is limited by the bottom wall of the recess and, of course, the outward movement of the core is limited by the wedging action of the core in the bore of the calk body. Now, it will be observed that as the 60 softer metal of the calk body wears out the ground engaging end of the calk body will wear faster than the core, and the more the soft metal of such body wears, the more the calk will project at its ground engaging end

and thus always provide a sharp gripping point for engaging with the ground. It will be noted that in case a calk should be broken off at the shoe, the threaded part of the calk may be readily removed, inasmuch as the peculiar shape of the core pin enables the latter to be easily loosened and a tool inserted in the bore from which the pin has been removed so that the broken piece of calk may be easily unscrewed by means of the tool and a new calk inserted, and it will further be noted that this insertion of the new calk may be accomplished without removing the shoe from the hoof for the purpose of heating such shoe and subsequently using a drill or punch to remove the stud or shank of the calk, as is necessary with the usual removable calk, the use of such punch or drill generally injuring the thread of the bore. It will also be seen that there is no shoulder on my calk to prevent it penetrating the ice clear to the shoe, and thus insuring a much better hold on the ice or ground than is possible with the ordinary form of calk. Yet such calk may be easily unscrewed or set with a wrench or similar tool.

I further wish to direct attention to the peculiar construction of the toe of my shoe, inasmuch as by forming it as hereinbefore described, I insure that the calks will be given the proper slant or pitch forward, thus insuring a much better hold on slippery surfaces, especially where great pulling effort is required on the part of the animal.

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims.

What I claim is:

1. The combination with a shoe having a threaded recess therein extending but part way through the shoe, of a calk comprising a tubular shank section adapted to be threaded into the recess, a body section of relatively soft metal having a tapered bore extending longitudinally therethrough and communicating with the tubular shank, and a tapered core pin of relatively hard material passing through the bore of the body section and having its inner end adapted to bear against the bottom wall of the recess and its outer end to project slightly beyond the outer or ground engaging end of the calk body.

2. The combination with a horse shoe having a threaded recess therein opening through the outer face of the shoe, of a calk having a tubular shank section threaded into

the recess and a tapered body section of relatively soft material formed integral with the shank section, said tapered body section having a tapered bore extending longitudinally therethrough and communicating with the tubular shank, and a core pin tapered to correspond to the taper of the bore passing through said bore and adapted to bear at its inner end against the bottom

wall of the recess of the shoe and to project 10 at its outer end beyond the ground engaging end of the calk.

In testimony whereof, I affix my signature, in the presence of two witnesses.

THOMAS SHEPHERD.
